Inventor:

Walter Sixt,

By Dymforth, Le, Critten & Miles,
Atty's.

UNITED STATES PATENT OFFICE.

WALTER SIXT, OF STREATOR, ILLINOIS.

SCUTTLE.

Application filed November 7, 1921. Serial No. 513,448.

To all whom it may concern:

Be it known that I, WALTER SIXT, a citizen of the United States, residing at Streator, in the county of La Salle and State of Illinois, have invented a new and useful Improvement in Scuttles, of which the following is a specification.

This invention relates to improvements in scuttles, and more particularly to a scuttle especially adapted for pouring cobs, coal or other material into a stove or similar device.

A device embodying the features of my invention is shown in the accompanying drawings, in which—

15 Figure 1 is a view in perspective of my improved scuttle, Figure 2 is a view in perspective of a stove, and Figure 3 is a view taken as indicated by the line 3 of Fig. 2, showing also a part of the scuttle in section 20 as the same is applied to the stove when in use.

As shown in the drawings, 10 indicates in general a scuttle which may be made in any ordinary form. This scuttle is provided at its forward end with a pouring spout, in the usual manner, as indicated by 11.

Fastened on the outside of the scuttle, under the pouring spout, are two parallelly arranged straps 12. These straps are attached to the scuttle in any suitable manner, for example by means of the rivets 13. The upper ends of the straps 12 project somewhat beyond the upper edge of the scuttle, and are bent to a substantially horizontal position, as indicated by 14. Just below the edge of the pouring spout, the straps 12 are provided with forwardly-projecting kinks as indicated by 15.

40 17 indicates in general a stove, which is here shown provided with a feeding pouch 18. 19 indicates the lid which covers the pouch. The outside upper edge of the pouch is indicated by 20.

45 In the use of the device, the scuttle 10 is filled with cobs or other material which

it is desired to pour into the stove. The scuttle is then placed in position so that the outer edge 20 of the feeding pouch is hooked between the ends 14 and kinks 15 of the straps 12. This holds the scuttle 10 in proper relation to the pouch, so that as the back part of the scuttle is raised, the cobs or other material will flow from the scuttle into the pouch without spilling. During all of the 55 pouring operation, the edge 20 of the pouch remains hooked between the ends 14 and kinks 15 of the straps 12, thus maintaining the edge of the pouring spout on the scuttle in proper relation to the feeding pouch on 60 the stove.

Although I have shown and described certain embodiments of my invention, it is to be understood that it is capable of many modifications. Changes, therefore, in the 65 construction and arrangement may be made without departing from the spirit and scope of the invention as disclosed in the appended claims, in which it is my intention to claim all novelty inherent in my invention as 70 broadly as possible in view of the prior art.

What I claim as new, and desire to secure by Letters Patent, is:

1. In combination with a scuttle, means adapted to engage with the edge of an opening to maintain the scuttle in fixed relation to said opening during the operation of pouring contents from the scuttle into the opening.

2. In combination with a scuttle, means 80 adapted to engage with the edge of an opening to maintain the scuttle in fixed relation to said opening during the operation of pouring contents from the scuttle into the opening, said means comprising strap members 85 attached to the scuttle, said strap members being provided with parts adapted to engage with one edge of the opening.

In testimony whereof I have hereunto set my hand this 4th day of November, 1921.

90

WALTER SIXT.
